(57) **CLAIM**

We claim the ornamental design for a safe, as shown and described.

DESCRIPTION

FIG. 1 is a front perspective view of a safe showing our new design;

FIG. 2 is a rear perspective view thereof;

FIG. 3 is a top view thereof;

FIG. 4 is a front view thereof;

FIG. 5 is a rear view thereof;

FIG. 6 is a bottom view thereof;

FIG. 7 is a right side view thereof; and,

FIG. 8 is a left side view thereof.

In the drawings, the broken lines in the FIGS. 1-8 depict portions of the design that form no part of the claim.

1 Claim, 5 Drawing Sheets
